UNITED STATES PATENT OFFICE.

RICHARD N. OAKMAN, JR., OF TURNER'S FALLS, MASSACHUSETTS.

DESIGN FOR TABLE-FORKS.

Specification forming part of Design No. **11,324**, dated August 5, 1879; application filed June 20, 1879.
[Term of patent 7 years.]

To all whom it may concern:

Be it known that I, RICHARD N. OAKMAN, Jr., of Turner's Falls, in the county of Franklin and State of Massachusetts, have originated and designed a new Pattern of Table-Forks, of which the following is a full, clear, and exact description, reference being had to the accompanying drawings, making a part of this specification.

The nature of my design is fully represented in the two figures of the drawings, of which Figure 1 is a front view, and Fig. 2 a back view. Figs. 3, 4, and 5, transverse sections.

Referring to drawings, A are the fork-prongs, of the usual form; B, the shoulder; C, the shank, and D the handle.

The shank C is thick and rounding toward the front, running into a flattened surface about midway between the shoulder B and handle at D.

On the face of the fork are beads *a*, which start on either side with volutes *b*, and, following the edge of the shoulder and shank, form, together with the curved surface of said shank, a groove, *c*. The said bead appears again as such when it reaches the flat surface of the handle, and, continuing around, forms the outline of the flat point *d*. A second bead, *a'*, follows within that of *a*, and extending toward the pointed end of the handle, is formed into a semicircle.

A triangular space ornamented with curved

rays is also outlined with a bead like that of *a*, and formed at the end of the fork-handle. Within the inner bead, at the semicircular curve at the handle, is a double spray of leaves and flowers, pinned with a rosette, as shown.

The triangular space near the shank of the fork is ornamented with a spray of leaves and flowers, *e'*, as is also the space *f* within the bead of the shoulder.

The back of the fork is ornamented with a bead to form its outline, which begins and ends with volutes between the shoulder and prongs. An inner bead similar to the inner one on the front completes the ornamentation of the back of the fork.

Having thus described my design, I claim—

1. The herein-described design for table-forks, consisting of the shoulder B, rounding shank C, and handle D, ornamented on the face side with beads *a a'*, volutes *b*, and rays in point *d*, flowers *e e'* in the flat space of said handle, and spray *e''* in the flat space of said shoulder B, as specified.

2. The fork described, having its back ornamented with double beading *a a'*, the latter of which begins and terminates with volutes *b*, and the triangular space at *d*, formed by the edge and curved beading, as specified.

RICHARD N. OAKMAN, JR.
